UNITED STATES PATENT OFFICE.

HARRY J. HANKEE, OF MINNEAPOLIS, MINNESOTA.

DESIGN FOR AN ELECTRIC AUTOMOBILE-SIGNAL.

53,164.

Specification for Design.

Patented Apr. 1, 1919.

Application filed January 23, 1918. Serial No. 213,423. Term of patent 7 years.

To all whom it may concern:

Be it known that I, HARRY J. HANKEE, a citizen of the United States, residing in the city of Minneapolis, county of Hennepin, and State of Minnesota, have invented a new, original, and ornamental Design for Electric Automobile-Signals, of which the following is a specification, reference being had to the accompanying drawing, forming part thereof.

Figure 1 is a perspective view of an electric automobile signal showing my new design; Fig. 2 is a side elevation and Fig. 3 is an end elevation thereof.

I claim:

The ornamental design for an electric automobile signal as shown.

HARRY J. HANKEE.
